Specification of Letters Patent. Patented Mar. 17, 1914.

Application filed May 10, 1913. Serial No. 768,726.

To all whom it may concern:

Be it known that I, RICHARD S. M. MITCHELL, a citizen of the United States, residing at Syracuse, in the county of Onondaga and State of New York, have invented certain new and useful Improvements in Transmitters, of which the following is a specification.

This invention relates to improvements in transmitters designed for use in connection with microphonic and telephonic devices generally, and the invention relates particularly to a novel construction of a 3-way transmitter which is adapted for use in connection with sound recording and reproducing machines, telephones and the like.

The object of the invention is to provide a vibrating diaphragm in combination with a plurality of opposed electrodes, and a plurality of variable and resilient resistants forming parts of the transmitting lines, the said variable resistants forming the electric connections between the diaphragm and the electrodes, and capable of alternate action for both increasing and decreasing the resistance in the transmitting lines.

The various features and parts will be understood from the detailed description which follows, and by reference to the accompanying drawing, in which—

Figure 1 is a top plan view of my improved transmitter. Fig. 2 is a central vertical cross-section, taken on line 2—2 of Fig. 1, showing the construction and arrangement 35 of the transmitter. Fig. 3 is a horizontal section taken on line 3—3 of Fig. 2. Fig. 4 is a horizontal section taken on line 4—4 of Fig. 2. Fig. 5 is a central vertical section, showing the construction and arrangement 40 of an ordinary 2-way transmitter, having my improvement applied thereto. Fig. 6 is an enlarged fragmentary section showing the method of attaching the spiral resistance coils to the opposite sides of the diaphragm of the 3-way transmitter. Fig. 7 is a diagrammatic view, showing a convenient arrangement of the transmitter circuits.

Similar characters of reference are assigned to corresponding parts throughout 50 the several views.

Heretofore, 3-way transmitters have consisted of carbon diaphragms which vibrate between two variable electrodes comprising granulated carbon. In these transmitters 55 the weight of the carbon and the pressure

of the retaining asbestos fiber, damp the diaphragm of the transmitter.

The object of my invention is to provide a 3-way transmitter, particularly adapted for use in connection with talking and similar sound reproducing machines, which has the same carrying capacity as the granulated carbon transmitters, and which has the additional advantage of extreme sensitivity, in that the resilient carbon elements 60 disposed between the opposed electrodes and the diaphragm, offer little or no resistance to the movements of the diaphragm, so that the slightest disturbance in the atmosphere in the immediate neighborhood of the instrument sets up a motion in the diaphragm with a resultant fluctuation of current due 65 to the reduction of the ohmic resistance in the carbon springs. In this way the ohmic resistance is decreased and increased, not 70 only by the parting of company between the electrodes and the diaphragm, but by the merest variation of the pressure brought to bear upon the surfaces of the springs, the diaphragm, and the electrode already in contact. Thus it will be readily seen that with 75 a higher resistance in the two resistants springs, the slightest motion of the diaphragm will bring a great number of convolutions of the springs or filaments into 80 contact with the electrodes, thus bringing about an enormous range of fluctuation in the circuits of the transmitters.

Referring to Figs. 1, 2, 3, 4 and 6 of the drawing, 2 represents the one-part back of 90 the 3-way transmitter, which is preferably made of nonconducting material, such as hard rubber, fiber and the like. The back 2 is preferably circular in form, and it is provided with a concentric boss or raised portion 3, which is hollow, and in which is disposed an electrode comprising a solid block 95 of carbon 4, which may be held in place by any suitable means. The body 2 has a peripheral flange 5, for providing a relatively 100 broad shallow recess 6, in which is disposed the diaphragm 7, which in the present case preferably consists of a relatively thin disk 105 of carbon, but any other suitable substance may be used if desired. The diaphragm 7 is 110 preferably supported in the chamber 5 by nonconducting rings 8, which are disposed on the opposite sides and adjacent the peripheral edge of the diaphragm, as best seen in Fig. 2. The rings 8 preferably consist of 115

small pliable rubber tubes, which are compressible and cushion-like, but the said rings may comprise any other suitable insulating material.

5 11 represents a circular cap, preferably made to the same diameter and of the same material as the back 2, which is employed for closing the open side of the back, to which it is secured by means of bolts 9, which pass through coinciding perforations formed in the back and the cap, as shown. The cap 11 has an embossed or raised portion 12, for providing a cavity 12', in which is disposed a second electrode comprising a 15 block of carbon 13, the latter being solid except for a series of perforations 14, which are grouped around the center of said carbon, and which are employed for carrying the vibrations of sounds to and from the 20 diaphragm chamber 6. The center of the boss 12 of the cap is provided with a relatively large opening 15 for receiving or emitting sounds, and 16 represents an integral horn or mouth-piece, which is arranged concentric to the opening 15, and which serves as a receiver and condenser for the sound-waves which actuate the diaphragm.

The diaphragm 7 of my improved 3-way transmitter connects with the opposed carbon electrodes 4 and 13 by means of two spirally wound coils, 17 and 18, the said coils preferably consisting of flexible and resilient carbon wire, although any other high-resistance material may be used for making the coils, and produce good results. The inner end of the coils 17 and 18 connect with the diaphragm, at or near the center thereof, while the outer ends of the said coils connect to the electrodes 4 and 13, as best seen in Figs. 2 and 6. Various means may be employed for connecting the coils 17 and 18 to the diaphragm 7, but I prefer to make the said connections in the manner shown in Fig. 6, which consists of perforating the diaphragm, and then inserting a wire tie 20 through the said perforations, the loop of the tie engaging and drawing the end of the coil firmly against the face of the diaphragm 50 when the free ends of the wire are drawn tight and lapped or otherwise arranged, and the ends of the wire may then be held in place by a drop of solder, as shown at 20'. In practice, the diaphragm is spaced only a few thousandths of an inch from the carbon parts 4 and 13, and in order to allow for the free vibratory movement of the diaphragm in opposite directions, the carbon parts 4 and 13 are provided with coinciding recesses 60 21, to receive the projecting ends of the ties 20, which bind the coils 17 and 18, as shown in Figs. 2 and 6.

22 represents a binding post for the carbon electrode 4, one end of which is suitably connected to the electrode. The opposite

end of the post 22 passes through and extends beyond the center of the casing 2, and is threaded to receive the usual nuts for securing the electric circuit wire 23.

24 represents a second binding post which 70 pierces the casing 2, and its outer end is threaded to receive a pair of nuts for gripping a wire 25. The inner end of the binding post 24 connects with one end of a metallic conductor 26, the opposite end of said conductor connecting with an annular metal ring 27 which is mounted upon the upper side of the diaphragm 7.

29 represents a third binding post, the inner end of which connects with the carbon 80 electrode 13, the outer end passing through the cap 11, and having threads for receiving nuts which grip a third wire 30.

Fig. 5 illustrates a modified form of my transmitter, in which 2' represents the back 85 or casing having a hollow raised portion 3', in which is disposed an electrode, which preferably comprises a solid block of carbon 4'. The back 2' is substantially like the corresponding part in the preceding figures, 90 and is arranged to provide a broad recess 6' in which is disposed a diaphragm 7', which is disposed between and supported by rings 8', which may consist of rubber tubing or felt. 12' represents the cap which closes 95 the open side of the casing, which is provided with an integral horn or mouth-piece 16' which is disposed concentric to the central opening 15', and through which the sound-waves are carried to the diaphragm. 100 17' represents a resilient carbon coil similar to the coils 17 and 18, and which forms the electric connection between the diaphragm and the electrode 4'. The spring 7' may connect with the diaphragm and the electrode 105 in any suitable manner, or as shown in Figs. 2 and 6. The transmitting line or circuit outside of the transmitter proper consists of wires 40 and 41. Wire 40 connects with the electrodes 4' by means of a binding post 110 42, as shown. The wire 41 connects with a binding post 43 which is held in place by a suitable insulating part 44, which is embedded in the upper side of the electrode 4'. The binding post 43 connects with the diaphragm 7' by means of a conductor 45, 115 which in turn connects with a metallic ring 46 which is carried by the diaphragm. In this modified form of transmitter, the sound-waves entering through the horn 16' vibrate 120 the diaphragm 7' which effects the alternate compressing and relaxing of the carbon spring 17', which decreases and increases the resistance offered by the said spring, thereby increasing and decreasing the fluctuations in the electric circuit comprising 125 the wires 40 and 41. The function and operation of the diaphragm 7' and the sensitive resistor 17' are substantially the same as that described for the similar parts in 130

the preceding views, excepting that these parts serve but a single transmitting line, instead of two, which renders the modified device peculiarly serviceable for telephones and like mechanisms.

Fig. 7 illustrates diagrammatically the arrangement of my 3-way transmitter in connection with a receiver 32. In Fig. 7 my transmitter appears disposed between conductors 33 and 34, wherein the wires 23 and 30 connect the transmitter thereto in parallel, while the wire 25 leads from the diaphragm 7 to one side of a battery 35, the opposite side of the battery connects by a wire 36 with the center of a line 37, the opposite ends of line 37 connecting with the corresponding ends of wires 33 and 34, and in line 37 I connect a fixed resistance, as shown at 38 and 38'. The opposite end of the wires 33 and 34 connect with the receiver 32.

The operation of my 3-way transmitter is as follows: When the diaphragm 7 is vibrated by the sound-waves coming to it through the horn 16 and the perforations 14, the diaphragm alternately moves toward and away from the electrodes 4 and 13. When the center of the diaphragm moves toward the electrode 4 it compresses the carbon resistance coil 17 toward said electrode, and forces a greater number of the convolutions of said coil against the face of the electrode 4, which lowers the resistance and thereby increases the current in the circuit comprising the wires 23 and 25. At the same time the diaphragm 7 having moved away from the electrode 13, disengages a number of the convolutions of the coil 18 from the face of the electrode 13, which increases the resistance and thereby decreases the current in the circuit comprising the wires 25 and 30. By this arrangement the current on either side of the diaphragm varies directly as the pressure of the diaphragm, when the diaphragm vibrates toward either of the electrodes 4 and 13 and the current through either of the said electrodes is thereby increased in exact ratio to the pressure exerted between the diaphragm and the electrodes. The increasing and decreasing of the resistance on the opposite sides of the diaphragm alternately increases and decreases the fluctuations in the electric circuits 23-25 and 25-30, and this increasing and decreasing of the resistance by the vibrations of the diaphragm, induces an alternating current in wires 33 and 34 and also in the receiver 32.

Owing to the spiral arrangement of the coils 17 and 18, the convolutions of the said coils never come in contact with each other, the current therefore must traverse the coils lengthwise instead of taking the shorter course by jumping from one convolution to the other. Under this arrangement when

the diaphragm is vibrated by the sound-waves entering the horn 16, the resistance on each side of the diaphragm is decreased or increased accordingly as a greater number of the convolutions are brought into engagement with, or disengaged from, the face of the electrodes. The carbon coils 17 and 18 are preferably of comparatively fine gage, and therefore have a relatively high resistance. Such being the case, a slight vibration of the diaphragm will effect a considerable increase or decrease in the resistance of the spirals 17 and 18 by lengthening or shortening the portions of the said coils which are free from contact with the electrodes.

By the provision of the resistance coils 17 and 18 disposed on the opposite sides of the diaphragm, and each connecting with a separate electrode, I am able to produce an extremely sensitive transmitter, and at the same time provide wide ranges of variations in the opposing resistances, which effect a correspondingly wide range of fluctuations in the electric circuits.

Having thus described my invention, what I claim as new and desire to secure by Letters Patent, is—

1. In a 3-way transmitter, the combination with the opposed solid carbon electrodes, and a vibrating diaphragm interposed between the electrodes, of a spiral resistant interposed between the diaphragm and each of said electrodes, said spiral resistants forming the electric connections between the diaphragm and said electrodes and capable of being alternately compressed and relaxed for simultaneously decreasing the resistance of one of said resistants, and for increasing the resistance of the other of said resistants.

2. In a 3-way transmitter, a pair of opposed electrodes spaced apart, a support for each electrode, a diaphragm interposed between said electrodes, a variable and resilient resistance interposed between the diaphragm and each of said electrodes and forming the electric circuit between the diaphragm and said electrodes, said resistants comprising spiral springs adapted to be compressed against the face of the electrodes for alternately decreasing the resistance of the variable resistance elements.

3. In a 3-way transmitter, the combination with a diaphragm and a solid carbon electrode disposed on each side of the diaphragm and spaced therefrom, a conductor for each electrode, a separate conductor for the diaphragm, and a pair of resilient spiral resistants, said resistants disposed on the opposite sides of the diaphragm, one end of each resistant connecting with the diaphragm, the opposite end of each resistant connecting with the corresponding electrode, the said resistants adapted to be simulta-

neously compressed and relaxed for increasing and decreasing the fluctuations in the transmitting lines formed by said conductors.

- 5 4. In a 3-way transmitter, the combination with a pair of spaced electrodes and a diaphragm interposed between said electrodes and insulated therefrom, of spiral resistants interposed between and connecting the diaphragm with each electrode, each of said resistants forming a part of an independent transmitting circuit, each of said resistants capable of being moved toward or away from the adjacent electrode for decreasing or increasing the resistance in one of said circuits, the variation in the resistance of said circuits being effected by the contact of the convolutions of said resistance with, or their release from the said electrodes.
- 10 5. In a 3-way transmitter, the combination with a pair of spaced electrodes, one being solid, the other having a series of perforations for the passage of sound-waves, of a vibrating diaphragm disposed between said electrodes, a pair of sensitive spiral springs, said springs disposed on the opposite sides of the diaphragm and connecting the diaphragm with the corresponding electrodes, and a horn for carrying the sound-waves to the perforated electrode.
- 15 6. In a 3-way transmitter, a pair of car-

bon electrodes, one of said electrodes being solid, the other electrode having a series of perforations, said electrodes spaced apart and having independent supports, a vibrating diaphragm interposed between said electrodes and insulated therefrom, an annular terminal carried by said diaphragm, means for connecting said electrodes for forming two separate electric circuits, wherein said annular electrode is common to both of said circuits, a variable resilient resistance coil disposed on each side of the diaphragm, one end of each coil connecting with the diaphragm, the opposite end connecting with the corresponding electrode, said coils adapted to complete the electric circuits between said electrodes and the annular electrode carried by the diaphragm, said coils capable of being alternately compressed toward said electrodes for decreasing the resistance in said circuits when the diaphragm is vibrated by sound-waves entering through the said perforations, said coils capable of being alternately relaxed by the vibrating of said diaphragm for increasing the resistance in said circuits.

In testimony whereof I affix my signature in presence of two witnesses.
